TROPHY BASE

Marvin Kramer and Harry A. Dorn, Chicago, Ill., assignors to General Classics, Incorporated, Chicago, Ill., a corporation of Illinois

Filed Mar. 21, 1958, Ser. No. 50,125

Term of patent 3½ years

(Cl. D29—23)

FIG. 1

FIG. 2

FIG. 3

FIG. 4

Fig. 1 is a front elevational view of a trophy base embodying our new design;

Fig. 2 is a side elevational view of the same;

Fig. 3 is a rear elevational view of the same; and

Fig. 4 is a sectional view taken on the plane of line 4-4 in Fig. 1 of the drawings and viewed downwardly in the direction indicated.

The side not shown is substantially the same as the side shown.

The essential features of our design reside in the portions shown in solid lines.

We claim:

The ornamental design for a trophy base, substantially as shown and described.
